UNITED STATES PATENT OFFICE

EMIL G. SAUER, OF RICHMOND HILL, NEW YORK, ASSIGNOR TO BIGELOW CARPET COMPANY, A CORPORATION OF MASSACHUSETTS.

DESIGN FOR A RUG.

44,809.

Specification for Design.

Patented Oct. 28, 1913.

Application filed September 9, 1913. Serial No. 788,979. Term of patent 3½ years.

To all whom it may concern:

Be it known that I, EMIL G. SAUER, a citizen of the United States, residing in Richmond Hill, in the county of Queens and State of New York, have invented a new, original, and ornamental Design for a Rug of Small Sizes, of which the following is a specification, reference being had to the accompanying drawing, forming part thereof.

The drawing illustrates one quarter of a rug showing my new design; the remaining three quarters become duplicates thereof when the one quarter shown in the drawing is reversed bi-symmetrically from the central axes, both horizontal and vertical.

I claim:

The ornamental design for a rug as shown.

EMIL G. SAUER.
